CAR-MOTOR MOUNTING.

1,386,586.

Specification of Letters Patent.

Patented Aug. 2, 1921.

Application filed May 27, 1918. Serial No. 236,853.

To all whom it may concern:

Be it known that we, HOWARD J. MURRAY, a citizen of the United States, and a resident of Brooklyn, county of Kings, and State of New York, and WALTER S. RUGG, a citizen of the United States, and a resident of Pittsburgh, county of Allegheny, and State of Pennsylvania, have invented certain new and useful Improvements in Car-Motor Mountings, of which the following is a specification.

The invention relates in general to an improvement in the power plants of electric locomotives or passenger cars, and specifically relates to the mounting of the motors and the power transmission elements in the electrically driven power plants in flange wheel railroad vehicles.

The invention has for its general object the reduction of unsprung supported weights, so as to reduce excessive wear and tear on the truck and power plant now prevalent in such constructions. It is proposed to arrange the power transmission elements in such a manner as to reduce the strains incidental to the transmission of power, thus reducing the weight of these parts and making possible the use of higher speed motors and power transmission parts than is now known. It is further proposed to install this improvement in conventional constructions with the least possible modification of the construction to effect the desired results.

In approved types of these electrical vehicles it is now common to drive the axles by means of a separate motor for each axle, which motor is usually supported directly or partially from the axle. This subjects the motor to undue shocks as the wheels pass over the joints and uneven places in the track, thus resulting in undue wear on the bearings, loosening of bolts, and deterioration of insulation and electrical connections, as well as undue wear and tear on the track.

Accordingly the invention contemplates a structure in which the motor is entirely removed from the axle so as to permit free play of the wheels as they pass over the rail joints and other variations in track level.

In the previous methods of mounting the motor on the driven axle there resulted a torque, which tended to rotate the motor

about the axle, thus putting a twisting strain on the motor frame, which tended to distort it and to disalign the motor shaft pinions and other transmission elements. For this reason it has been impossible to make the close fit essential to the efficient transmission of power, as it was necessary to allow large tolerances to keep the power transmission devices in operative position.

Accordingly the invention contemplates the mounting of the motor so that it is cushioned or spring-supported relative to the axle, and it is further proposed to couple the motor with the axle in such a manner as to allow relative independent movement therebetween while maintaining the highest possible transmission efficiency.

Incidental to the last mentioned object, it is proposed to mount the transmission in an inclosing gear case, which will be independent of motor vibration, will be supported from the axle and assist in maintaining the transmission elements in proper driving connection with the axle under all conditions of use.

In the conventional car and locomotive structures, the available space in which is possible to position a motor and any multiplying gear connection is so limited by the presence of steam and air pipes, braking and signal systems and the like, that the disposition of the power plant for transmission efficiency is affected by the prefixed disposition of these different parts on the conventional constructions. Another object of the invention, therefore, is to perfect an organization of power plant parts capable of being installed in the limited available space and at the same time obtain the maximum possible transmission efficiency.

Various other objects and advantages of the invention will be in part obvious from an inspection of the accompanying drawings and in part will be more fully set forth in the following particular description of one form of mechanism embodying the invention, and the invention also consists in certain new and novel features of constructions and combination of parts hereinafter set forth and claimed.

In the accompanying drawings there is illustrated one embodiment of the invention shown in connection with a vehicle of the conventional passenger type, and reference is made to two co-pending applications Serial

Nos. 336,854 and 236,855 filed under even date and entitled Motor casing truck construction and Single motor bolster, which show two other embodiments of the invention in connection with vehicles of the locomotive type.

In the drawings:

Figure 1 is a plan view, looking down upon the wheel truck of a passenger car equipped with a preferred embodiment of my invention, and with parts broken away to show internal motor and power transmission construction;

Fig. 2 is a longitudinal sectional view taken on the broken line 2—2 of Fig. 1, looking in the direction indicated by the arrow; and

Fig. 3 is a transverse sectional view taken on the line 3—3 of Fig. 1.

In the accompanying drawings there is illustrated a portion of car truck frame of the passenger type, together with a wheel truck element of the two axle type.

As part of the car truck frame 10 there is shown side sills 11, a truck bolster in the form of a casting 12, and a pair of transoms 13 and 14 co-acting to form the rigid frame structure usual in devices of this character.

For convenience in identification one of the transoms 13 will be considered as the forward support and the other transom 14 as the rear support. The transoms are similar in construction, are positioned on opposite sides of the bolster 12, and are H-shaped in plan to form, in effect, a centrally disposed motor supporting frame 15. Extensions project laterally from opposite sides of the frame 15 to form a pair of parallel support elements 16, opposite ends of which are hung from the side sills and fastened thereto by bolts 17. The car truck includes pedestals 18, in which are journaled a pair of running gears 19 and 20, positioned respectively in advance of the forward support 13 and in rear of the rear support. The bolster is resiliently supported from the truck by the transversely disposed elliptical springs 22, and the four upright coiled springs 23. The running gears each include a shaft 24, provided with flange wheels 25, all as is usual in one well known form of car construction.

Each of the axles is separately driven by means of a geared connection, the forward running gear 19 being driven from a rearwardly disposed electric motor 26, and the rear running gear 20 being correspondingly driven from a forwardly disposed motor 27. The motors are positioned on opposite sides of the longitudinal medial line through the vehicle, and on opposite sides of the bolster 12. The motors are mounted to drive the remote axle, and the driving connections with the oppositely disposed axles lapping

each other, when considered transversely of the underframe, so as to provide within the limited space available between the two axles a relatively long driving connection between each motor and its correlated axle.

70

The detail description of either driving unit will apply to the other except for obvious changes in direction, it being understood that corresponding parts are symmetrically disposed on opposite sides of the king pin opening 28.

75

The motors illustrated differ from conventional car driving motors, in that they may be of a higher speed type and are of lighter construction. The motors are underslung beneath the supports, and are fastened to the frames 15 by bolts 29. However, it is apparent that the motor casings may be cast integrally with the bolsters, thus eliminating the necessity of separately fastening these parts in position. The motors are positioned so as to bring each of the axes of rotation of their armature shafts 30 substantially in line with and intersecting the axis of rotation of its driven axle.

80

The armature shaft 30 (Fig. 2) is in the form of a hollow sleeve, with the end thereof adjacent its driven axle open, and its opposite end closed by means of a universal pivoting cap 31. It is obvious, however, that the shaft may be coupled to the armature shaft without closing this end of the armature shaft, thus facilitating the inspection of the armature shaft through its open end. The driving connection with the axle includes a relatively long driving shaft 32, which extends longitudinally of the vehicle through the armature shaft, and has one end fastened by means of a universal joint 33, to the end cap 31. The shaft and sleeve are so proportioned that the free end of the shaft is capable of some slight play in all directions without contacting with the armature sleeve shaft and the length of the shaft is so proportioned that the free end is capable of a material movement before there is any danger of contacting with the sleeve. The portion of this shaft exterior of the motor extends across and beneath the casting 12 toward the axle driven by the shaft.

110

The driving shaft 32 actuates a reducing gear train, which acts directly on the wheel axle. This gear train includes a relatively large bevel gear 34, keyed to the axle and enclosed within a housing 35 flexibly supported at one end from the adjacent bolster, and at the other end loosely mounted upon the hub of the large gear 34. Anti-friction bearings 36 are positioned between the casing and the hub of the gear, which hub has been elongated to provide extensive surfaces for supporting the bearings. A small bevel gear 37 meshes with the gear 34, and is revolvably mounted for rotation about a horizontal axis. This provides a self-contained effi-

115

120

125

130

cient gear train capable of being assembled in a shop and applied to the vehicle by pressing the large gear onto the axle.

When the parts are in normal position the axis of rotation of this small gear is coincident with the axis of rotation of the driving armature shaft and both axes intersect the axis of rotation of the axle. This small bevel gear is made with the least possible number of teeth to effect an economic drive so as to maintain a high reducing gear ratio between the motor and axle. The gear 37 is mounted centrally on a short driven shaft 38, with the end adjacent the axle mounted 15 in a bearing 39, constituting part of the housing 35 carried by the axle. The opposite end of the driven shaft is let into and pinned to a sleeve 40. This sleeve constitutes the inner face of a compound anti-friction bearing 41, mounted within an extension 42 from the transmission housing 35. This bearing 41 is designed to take up end thrust as well as radial loads on the short shaft. By this construction it is seen 20 that the end of the driven shaft adjacent the axle together with its small gear takes part in all movements of the axle and its attached large gear, so that in all positions of the axle the gear train formed by the gears 34 and 36 are maintained in this prefixed driving engagement. The sleeve 40 is connected to the adjacent end of the driven shaft 32 by means of a universal coupling 43, one element 44 of which has a square fit 25 within the sleeve so as to permit relative movement between the motor and axle in a direction longitudinal of the vehicle.

In operation it will be understood that the motors will transmit their high rotary speed 40 through the driving connection to the reducing gear connection, and from this reducing gear train power is applied directly to the axle to turn the flange wheels.

As the motors are mounted directly on the 45 transoms, which in turn are resiliently supported from the running gear, the hammering effect of motor weighted axles has been eliminated, thus saving wear and tear on the tracks and insuring an easier and more even 50 riding of the vehicle than has heretofore been possible. At the same time the resilient mounting of the motors has to a large extent eliminated the jarring of the motors, minimizing the wearing of their relative 55 movable parts, and deterioration of insulation and electric connections. This permits the use of such refined mechanism as ball bearings and the like, to reduce frictional losses.

60 The weight of the motors and co-acting parts is distributed on the truck frame, and is balanced on opposite sides of the longitudinal medial line. Further, the parts are diametrically disposed with reference to the 65 king pin casting, all of which co-acts to

form a well braced underframe, free of distortional strains.

The flexible drive between the motor and gear train, together with the use of a self-contained rear casing with bearings between the gear casing and the hub of the gear, has eliminated all twisting strains on the gears, pinions, and motor frames, thus permitting a better maintenance of alinement, a greater life to the parts, and a more efficient operation.

By placing the motor for driving one axle as close as possible to the other axle, all of the available space longitudinally between the axles is utilized to provide a long 80 driving shaft. This shaft is pivoted to the motor in such a way that relative vertical movement between the motor and axle is permitted with the least possible angular change between the axis of the driving shaft 85 and the axis of the armature shaft. In this way the straight line drive between these two members is maintained as far as is physically possible.

Having thus described our invention, we 90 claim:

1. In a railroad vehicle, the combination with a wheel truck, having unsprung parts including wheels with a driven axle mounted in said truck and having some freedom 95 of movement relative thereto, and spring supported parts including a frame structure having side sills with a plurality of side sill supporting springs supported from said unsprung parts, of a power unit for driving the wheels including a high speed electric motor hung from said resiliently supported frame structure and capable of vertical movement relative to the axle to bring its armature in line horizontally with said axle, and a flexible driving connection between said motor and axle, said connection including means for reducing the speed 100 of rotation of the motor transmitted to the axle.

2. In a device of the class described, the combination with a truck frame including side sills, and a one-piece casting fitted between the side sills to assist in bracing the truck frame, said casting including a motor support and constituting a wide spreading transom connecting the side sills, a wheel truck, an axle mounted in said truck, resilient means for supporting the truck frame from the wheel truck, a centrally positioned motor for driving the axle fixed to said motor support and free to move slightly about the axis of the axle and a flexible power drive between said motor and axle, said drive including a gear train 115 including meshed gears with their axes of rotation fixed relative to the axis of rotation of the axle.

3. In a device of the class described, the combination with a truck frame including 120

- side sills, and a one-piece casting fitted between the side sills to assist in bracing the underframe, said casting constituting a motor support and spaced apart transom elements 5 rigidly connecting the side sills, a wheel truck, an axle mounted in said truck frame, resilient means for supporting the casting from the wheel truck, a motor for driving the axle fixed to said motor support and 10 having a slight freedom of motion about the axis of the axle and a flexible power drive between said shiftable motor and axle.
4. In a device of the class described, the combination of an unsprung weight including a wheel truck, an axle journaled in said truck, a relatively large gear operatively connected to said axle, a bearing carried by said axle to move vertically therewith, a driving shaft mounted in said bearing, a 15 relatively small gear fixed to said shaft and meshing with said large gear to form a reducing gear train, a truck frame including a transom rigidly connected to the frame and free to move therewith relative to the 20 axle, truck frame supporting springs positioned between the wheel truck and the truck frame, a high speed motor carried by said transom, and a universally flexible driving connection between the motor and 25 said shaft.
5. In a device of the class described, the combination of a wheel truck, an axle journaled in said truck, a relatively large gear operatively connected to said axle, an anti-friction bearing carried by said truck, a driving shaft mounted in said bearing, a relatively small gear fixed to said shaft and 30 meshing with said large gear to form a reducing gear train, a resiliently mounted high speed motor, including a hollow armature shaft, and a driving shaft pivotally connected adjacent one end to the driving shaft, extending through said hollow armature shaft, and having its other end pivoted 35 to said armature shaft, thereby providing a long driving shaft.
6. In a device of the class described, the combination of a truck frame including a transom, a wheel truck including an axle, 40 means for supporting the truck frame resiliently from said wheel truck, a running gear journaled in the wheel truck, a motor supported from the transom, said motor and axle having a slight freedom of relative 45 movement in all directions, and a flexible driving connection between the motor and running gear, said connection including 50 mountings for supporting certain rotary parts of the connection, the axes of which 55 are fixed and permitting flexibility between 60 motor and axle while maintaining a fixed driving connection in the certain rotary parts of the connection.
7. In a device of the class described, the combination of a truck frame, a wheel truck,

means for supporting the truck frame resiliently from said wheel truck, a running gear journaled in the wheel truck, a motor supported from the truck frame for driving the running gear and a flexible driving connection 70 between the motor and running gear, said connection including a medium for transmuting the high speed rotation of the motor into relatively low speed at the axle and including a universal joint with 75 the rotary parts keyed together to prevent relative rotary movement and otherwise free for permitting relative movement in all other directions of opposite ends of said connection including relative movement longitudinally of the axis of rotation.

8. In a device of the class described, the combination of a truck frame, a wheel truck, means for supporting the truck frame resiliently from said wheel truck and otherwise 80 free of the same for independent relative movement, a running gear journaled in the wheel truck, a motor suspended from the truck frame and provided with an armature, a flexible driving connection including 85 mountings for supporting certain rotary parts of the connection, the axes of which are fixed, a relatively large driven gear fixed to the axle, a sleeve provided with a relatively small driving gear, meshing with 90 said large gear and coacting to constitute a reducing gear set, a universal coupling pivotally connected to the armature and having an element keyed in said sleeve to permit relative movement between the motor and 95 axle in a direction at right angles to the axle.

9. In a device of the class described, the combination with a wheel truck, a wheel-driving-power axle mounted in said truck, 105 an electric motor resiliently supported from said truck and provided with a hollow armature shaft extending at right angles to the axle, and a flexible driving connection between the motor and axle including a driving 110 shaft extending through the hollow armature shaft and pivotally connected thereto adjacent the end thereof opposite the axle.

10. In a device of the class described, the combination with a wheel truck, a wheel-driving-power axle mounted in said truck, an electric motor resiliently supported from said truck and provided with a hollow armature shaft extending at right angles to the axle, a flexible driving connection between 115 the motor and axle including a driving shaft extending through the hollow armature shaft and pivotally connected thereto at the end thereof opposite the axle, and a reducing gear train between the driving shaft and the 120 axle.

11. In a device of the class described, the combination with a truck frame, a pair of electric motors mounted in said frame and each having a hollow armature shaft dis- 130

posed parallel to and lapping each other on opposite sides of the longitudinal medial line of the vehicle, a pair of driving-axles mounted on opposite sides of the motors, means for supporting the motors resiliently from the axles and flexible driving connections between each of the motors and the axles farthest removed therefrom, said connections each including a driving shaft extending through its correlated hollow armature and fastened thereto at the end of the armature farthest removed from the axle driven thereby, so as to provide a relatively long driving connection between the closely positioned motors and their correlated axles.

12. In a device of the class described, the combination of a wheel truck, a wheel driving-axle mounted therein, a motor resiliently supported from said truck, and having a hollow armature shaft horizontally disposed and positioned with its axis substantially at a level of the axis of rotation of the axle and extending at right angles thereto, and a flexible driving connection between the motor and axle, said connection including a driving shaft extending through the armature shaft and pivotally connected thereto at the end thereof farthest removed from the axle.

13. In a device of the class described, the combination of a pair of running gears, each including an axle, a pair of wheels fixed to and driven by their shaft, and a gear containing casing fixed to each axle and extending lengthwise thereof, a pair of motors positioned between the axles, a driving connec-

tion extending from one of the motors to the farthest removed axle, a part of said driving connection including gears mounted in the casing on said farthest moved axle, a second driving connection similarly connecting the other motor with the other axle, a part of one of the motors, the gear casing and a part of the driven connection with the other motor being positioned in the space between one of the pair of wheels whereby the space between the pair of wheels is utilized.

14. In a device of the class described, the combination of a pair of running gears, each including an axle and a pair of wheels fixed to and driven by their coating shaft, a pair of floating transoms, a pair of motors positioned between the axles and hung respectively from and extending below said transoms whereby to bring the motor armatures substantially on a horizontal level with the axles, a driving connection extending horizontally from one of the motors to the farthest removed axle, a second driving connection similarly connecting the other motor with the other axle and extending parallel to the first named connection, a part of one of the motors and a part of the driven connection with the other motor being positioned side by side in the space between one of the pair of wheels whereby a part of the space between the pairs of wheels is utilized.

This specification signed this 20th day of May, 1918.

HOWARD J. MURRAY.
